UNITED STATES PATENT OFFICE

162,856

ADJUSTABLE WRENCH

Edward Matthews, Denver, Colo., assignor of one-half to Joseph H. Conway, Denver, Colo.

Application June 29, 1949, Serial No. 3,609

Term of patent 14 years

(Cl. D54—16)

To all whom it may concern:

Be it known that I, Edward Matthews, a citizen of the United States, resident of Denver, State of Colorado, have invented a new, original, and ornamental Design for Adjustable Wrench, of which the following is a specification, reference being had to the accompanying drawing, forming a part hereof.

Fig. 1 is a perspective view of an adjustable wrench, showing my new design;

Fig. 2 is a rear elevation, and

Fig. 3 is a side elevational view.

I claim:

The ornamental design for an adjustable wrench, as shown.

EDWARD MATTHEWS.
